FISHHOOK REMOVER

Heywood V. Kleber, Jr., P.O. Box 4, Glenbrook, Oreg.

Filed Jan. 15, 1965, Ser. No. 83,467

Term of patent 3½ years

(Cl. D31—4)

Fig. 1

Fig. 2

FIGURE 1 is a front elevational view of a fishhook remover showing my new design.

FIGURE 2 is a side elevational view of FIGURE 1 turned through 90 degrees.

I claim:

The ornamental design for a fishhook remover, substantially as shown.
